OVERHEAD RABBIT CARRIER FOR DOG-RACING TRACKS

Application filed June 20, 1928. Serial No. 286,927.

This invention relates to amusement devices and more particularly to a carrier for a rabbit or the like employed as a lure in connection with racing tracks.

5 At the present time it is customary when building a dog racing track to dig a trench and in this trench erect rails along which a carriage moves but this has been found unsatisfactory as it is expensive to install and 10 in addition it has been found dangerous and also water accumulates in the trench and is liable to cause a short circuit which would interfere with proper operation of the carriage.

15 Therefore, one object of the invention is to provide an overhead track which may be erected at a small cost and may, in fact, be carried by poles ordinarily employed as supports for lights by means of which the race 20 track is illuminated.

Another object of the invention is to so arrange the rails that there will be no danger of a person being injured by striking one of the rails when walking beneath the track and 25 further to so arrange the rails that, if a person, standing or walking beneath the rails should grasp one of the rails, there will be no danger of injury by an electric shock.

Another object of the invention is to allow 30 a three phase motor to be employed as the propelling means and thereby allow the carriage to be quickly stopped and returned to the starting point when necessary by merely reversing the polarity of the current passing 35 through upper rails of the track.

Another object of the invention is to provide an improved type of carriage having lower wheels which rests upon a lower rail of the track and upper wheels which are yieldably supported and urged into position to 40 bear against upper rails of the track where they serve to retain the carriage upon the track and also constitute rotatable contacts through which current may pass from the 45 charged upper rails to a motor carried by the carriage.

Another object of the invention is to so mount the motor that it may be adjusted in order to tighten a belt or chain which transmits rotary motion from the motor shaft to

axles carrying the wheels which rest upon the lower rail of the track.

Another object of the invention is to prevent danger of the dogs being injured in case the speed of the carriage should unexpectedly become reduced. It sometimes happens that due to a defect the carriage will slow down and as the dogs usually attack the rabbit from the front if they should catch it there is danger of a dog being caught between the rabbit and the surface of the race track. This often causes serious injury to the dog and, therefore, I propose to eliminate this danger by supporting the rabbit upon an arm or rod pivoted to the carriage so that if a dog should catch the rabbit the arm may swing upwardly when the rabbit is struck and thereby prevent danger of the dog being caught between the rabbit and the surface of the race track.

Another object of the invention is to so connect the rabbit with the arm carrying the same that if the rabbit should become torn by a dog it can be very easily removed and a new one substituted.

Another object of the invention is to provide the track with a shield disposed over the same and serving to protect the rails and carriage in case of rain.

Another object of the invention is to allow a light to be substituted in place of a rabbit in case dogs are being raced which prefer to follow a light instead of a stuffed rabbit.

The invention is illustrated in the accompanying drawings, wherein

Figure 1 is a view showing the carriage and portions of tracks upon which it is mounted in side elevation;

Fig. 2 is a transverse sectional view through the track with the carriage shown in end elevation;

Fig. 3 is a top plan view of the carriage;

Fig. 4 is a transverse sectional view through the upper rails and shield;

Fig. 5 is a fragmentary view illustrating a latch which serves to engage the rabbit carrying arm and releasably hold the arm in a raised position when swung upwardly out of its normal position;

Fig. 6 is an enlarged sectional view through

the rabbit taken on the line 6—6 of Fig. 1 and illustrating the manner of releasably securing the rabbit to the arm carrying the same, and

5 Fig. 7 is a fragmentary view of the arm showing a light substituted for a rabbit.

When constructing a race track for dogs, such as gray hounds, whippets and the like, poles or standards 1 are erected in spaced relation to each other along the inner side of the track in order to carry lights by means of which the track is illuminated and I employ these poles and secure to the same upper and lower arms 2 and 3 which are spaced 10 from each other vertically of the pole. The arms may be secured to the poles in any desired manner, but in the accompanying drawings I have shown these arms secured by bolts 4 and plates 5 and in order to prevent the arms from sagging I have provided braces 6 secured to the arms and poles by bolts 7. Lights have been omitted, but it will be understood that they will be applied to the poles in the usual manner. Upper rails 15 8 and 9 are secured against the under surfaces of the arms 2 in transverse spaced relation to each other and a lower rail 10 is secured against the upper surfaces of the arms 3 midway the rails 8 and 9, as clearly shown in 20 Fig. 2, and it is intended to have the lower arms at such height that a person may walk beneath the track without danger of striking the lower rail or its supporting arms. It should be further noted that since the upper 25 rails are charged and the lower rail is a dead rail there will be no danger of a person receiving a shock if an unusually tall person should happen to strike the rail or a person should grasp the rail when standing near it 30 or walking beneath it.

In order to protect the track from rain, I employ a shield 11 which consists of strips of sheet metal curved transversely, as shown in Fig. 4. The strips of metal from which the shield is formed extend between the poles and rest upon blocks or bolsters 12 which have curved upper surfaces and flat under surfaces so that they may be well supported upon the upper rails, and in order to firmly hold 35 the bolsters in engagement with the rails, I employ blocks 13 which bear against the rails and are firmly held in engagement with the rails and bolster by securing bolts 14. By this arrangement the shield will be very firmly held in place but at the same time it can be removed if found necessary or desirable.

The carriage which travels along the track includes a body portion or plate 15 formed of strong metal and substantially triangular in 40 shape. An opening 16 is formed in the central portion of the plate or body and through this opening extends an electric motor 17 from which extend side ears 18 having vertically extending slots 19 formed therein 45 to receive securing screws 20 which are

threaded into the body plate. By loosening these screws the motor may be vertically adjusted for a purpose to be hereinafter set forth. Bearings 21 and 22 project transversely of the body plate from the lower corners thereof, and these bearings receive axles 23 which have their ends projecting and carrying supporting wheels 24 to rest upon the lower rail 10 and sprocket wheels 25 engaged by a sprocket chain 26 which also engages a sprocket wheel 27 fixed upon the shaft of the motor 17. From an inspection of Fig. 1, it will be seen that, when the screws 20 are loosened, the motor may be shifted upwardly through the medium of the set screw 28 until the sprocket chain has been tightened and the screws then again tightened in order to firmly hold the motor in a set position. Therefore, the motor may serve as a tightener for the chain. It will be understood that if so desired pulleys may be substituted for the sprocket wheels 25 and 27 and a belt trained about the pulleys in place of the sprocket chain.

The upper wheels 29 which bear against the charged rails 8 and 9 are rotatably supported upon axles 30 which extend through but are insulated from bearings 31 at the upper ends of arms 32 which may be referred to as trolley poles, and these trolley poles are pivotally mounted at their lower ends, as shown at 33, and pass through clips 34 which serve to guide and limit pivotal movement of the trolley poles. Springs 35 are connected with eyes 36 which project upwardly from the bearings 31 and at their other ends are engaged with bolts 37 which pass through brackets 38 and carry securing nuts 39 so that by tightening or loosening the nuts the tension of the springs may be controlled. These springs exert a pulling action against the trolley poles and serve to retain the wheels in contacting engagement with the upper rails. Therefore, when the carriage is disposed between the upper and lower rails, the upper wheels will have good contacting engagement with the charged rails and may serve very effectively as current collectors and in addition there will be no danger of the carriage jumping the track when in motion. The motor is a three phase motor and has one wire 40 grounded upon the body plate, as shown in Fig. 1, and its other wires 41 secured to the axles upon which the collecting wheels 29 are mounted. By this arrangement the direction in which current passes through the motor may be controlled by reversing the polarity of the rails 8 and 9 and, therefore, the carriage may be caused to move forwardly when the dogs are racing and when it is desired to stop the carriage and return the carriage to the starting point it is merely necessary to reverse the polarity of the rails and this will cause the motor to reverse thereby rapidly checking the forward motion of the carriage 45 50 55 60 65 70 75 80 85 90 95 100 105 110 115 120 125 130

and causing it to return to the starting place.

In order to carry an artificial rabbit, I have provided an arm or rod 42 which may be hollow or solid and this rod is of such length that when disposed in the substantially vertical operative position shown in Figs. 1 and 2 the rabbit 43 carried by the rod will be disposed close to the track but at a sufficient distance above the surface thereof to prevent it from having contact therewith as it moves along the track. In order to secure the rabbit, I have provided a saddle plate 44 formed of metal and curved transversely, as shown in Fig. 6, so that it has close contacting engagement with the back of the rabbit. A spur 45 projects downwardly through the saddle plate into the body of the stuffed rabbit and at one side the saddle plate carries short straps 46 to which buckles 47 are attached while at its other side the saddle plate carries longer straps 48 which are passed about the rabbit and engaged with the buckles 47. By this arrangement the rabbit will be firmly held in place and prevented from being twisted out of its proper position but if a dog should catch and tear the rabbit the straps 48 can be released from the buckles and a new rabbit substituted very easily and quickly. A sleeve 49 fits loosely upon the bearing 22 and is formed with a sleeve extension 50 which is fixed upon the rod 42 in spaced relation to its upper end and the upper end portion of the rod is bent, as shown in Fig. 1, to provide a handle portion 51 of such length that it may be engaged between the jaws of a clamp 52 secured against the adjacent side face of the body plate 15. It should be noted that the jaw 53 of the clamp is pivotally mounted and engaged by springs 54 so that, while the rod will be normally retained in the position shown in Figs. 1 and 2, the handle may be moved from between the jaws and the rod swing upwardly to the position indicated by dotted lines in Fig. 1 if a dog should catch the rabbit and strike it. As previously explained, a dog when chasing a rabbit will strike it from the front and it is desired to have the arms swing upwardly in a rearward direction when the rabbit is struck so that there will be no danger of the dog becoming caught between the arm and the surface of the track and injured. Ears 55 extend downwardly from the bearing 21 and carry spring clips or jaws 56 which may be formed, as shown in Fig. 5, and are provided with heads 57 at their ends so that, when the rod is swung upwardly, it will be engaged between these clips and retained in an elevated position where it will be prevented from dropping downwardly and possibly injuring a dog upon the track by striking it. It will also be obvious that when the device is not in use the arm may be swung upwardly by an attendant so that it will be out of the way and

not liable to be accidentally struck and bent by some one walking along the track.

When the apparatus is erected, the arms 2 and 3 are secured to the poles 1 which may already be in place or poles erected for this purpose and, as previously stated, the poles are to carry the lights by means of which the track will be illuminated. The upper and lower rails are secured to the arms in approximately the relation to each other shown in Fig. 2 and power wires connected with the upper rails so that current may be supplied to these rails. The carriage is set in place upon the track with its lower wheels resting upon the rail 10 and its upper wheels bearing against the rails 8 and 9 and these upper wheels constitute trolley wheels to take current from the charged upper rails and deliver it to the motor. The arm or rod 42 normally extends downwardly from the carriage in spaced relation to the free ends of the arms 3 and the lower portion of the rod is bent transversely away from the lower arm 3 and then again downwardly, as shown in Fig. 2, so that the rabbit will be disposed in proper relation to the race track. When the power is turned on, the motor will be energized and the carriage will move along the track at a high rate of speed and the dogs will chase the rabbit. By proper control of the current the speed at which the carriage moves may be regulated and, therefore, the rabbit can be retained any distance in front of the dogs. After the race is ended the current is reversed and this will cause the motor to reverse, thereby quickly stopping the forward movement of the carriage and causing it to return to the starting point.

In Fig. 7, there has been shown a light 58 which may be employed in place of the rabbit. This light which consists of an electric bulb is screwed into a socket 59 mounted at the lower end of a hollow rod 60 corresponding to the rod 42 and wires 61 extend through the hollow rod and these wires project outwardly from the rod adjacent the sleeve 50 and may be cut into the wires of the motor so that when the current is turned on the light will be illuminated so that it may be followed by the dogs which prefer a light to a stuffed rabbit.

Having thus described the invention, I claim:

1. In a race track apparatus, an overhead track including upper and lower rails, a carriage between the rails having wheels engaging the rails, a motor carried by said carriage for propelling the same along the track, an arm pivotally connected with said carriage and normally disposed vertically, a lure carried by said arm at its lower end, the upper portion of the arm constituting a handle, a latch carried by said carriage to engage the handle and releasably hold the arm in a vertical position, and a second latch carried by

said carriage to engage the arm when swung upwardly and retain the arm in an elevated position.

2. In a race track apparatus, an overhead track, a carriage movable along said track, an arm pivoted to said carriage and normally disposed in a substantially vertical position with its lower portion extending below the track, a lure carried by the lower end of said arm, the upper portion of said arm constituting a handle, a latch carried by said carriage to engage the handle and releasably hold the arm in a vertical position, said arm being adapted to be swung upwardly to an inoperative position when released from said latch, and a second latch carried by said carriage to engage the arm when swung upwardly and releasably hold the arm in an elevated position.

3. In a race track apparatus, an overhead track including supporting poles, arms extending transversely from the poles one above another, rails secured against the upper arms and extending beneath the same in transverse spaced relation to each other, a rail secured to the lower arm below space between the upper rails, one of the upper rails being charged, a carriage between the rails having upper and lower wheels bearing against the same, the wheels engaging the upper rails receiving current therefrom, a motor carried by said carriage and having conductors connected with the upper wheels, an arm carried by said carriage and extending downwardly therefrom, and a lure carried by said arm.

4. In a race track apparatus, an overhead track including supporting poles, arms extending transversely from the poles one above another, rails secured against the upper and lower arms and extending between the same, a carriage movable along the track and having wheels bearing against the upper and lower rails, an arm pivoted to said carriage and normally extending downwardly therefrom, a lure carried by said arm, means to releasably retain the arm in a normal position, and means to secure the arm when swung upwardly to an inoperative position.

5. In a race track apparatus, an overhead track including supporting poles, arms extending transversely from the poles one above another, rails secured against the upper arms and extending beneath the same in transverse spaced relation to each other, a rail secured to the lower arm below space between the upper rails, one of the upper rails being charged, a guard for said track consisting of strips disposed over the upper rails between the poles, bolsters upon the upper rails firmly secured in transverse relation thereto and having the strips secured against their upper surfaces, a carriage movable along the track and having wheels engaging the upper and

lower rails, a motor carried by said carriage and receiving current from the upper wheels and operatively connected with the lower wheels, and means carried by the carriage to support a lure below the track.

6. In a race track apparatus, an overhead track including supporting poles, arms extending transversely from the poles one above another, rails secured against the upper and lower arms and extending between the same, a guard for said track extending between the poles over the upper rails, a carriage movable along the track and having wheels bearing against the upper and lower rails, and means carried by the carriage to support a lure below the track.

7. In a race track apparatus, an overhead track including upper rails spaced transversely from each other and a lower rail disposed below space between the upper rails, a carriage between the rails having lower wheels resting upon the lower rail, poles pivoted to the carriage and extending upwardly therefrom, wheels rotatably connected with said poles, resilient means urging said poles upwardly to retain the wheels carried thereby in engagement with the upper rails, an electric motor carried by said carriage, the motor being grounded upon the carriage and having conductor wires connected with the poles whereby current may be fed from the upper rails to the motor, means for transmitting rotary motion from the motor to the lower wheels and propel the carriage along the track, an arm carried by said carriage and extending downwardly therefrom, and a lure carried by said arm at the lower end thereof.

8. In a race track apparatus, an overhead track including upper rails spaced transversely from each other and a lower rail disposed below space between the upper rails, a carriage between the rails having lower wheels resting upon the lower rail and upper wheels yieldably held in position to bear against the upper rails, an electric motor carried by said carriage, said motor being grounded upon the carriage and having wires connected with the upper wheels whereby current may be fed to the motor from the upper rails, drive means between the motor and lower wheels, and a lure carried by said carriage and disposed between the track.

9. In a race track apparatus, an overhead track, a carriage movable along said track, an arm pivoted to said carriage and normally disposed in a substantially vertical position with its lower portion extending below the track, a saddle plate at the lower end of said arm, a spur extending from the saddle plate below the arm, a lure fitting against the saddle plate with the spur embedded in the lure, securing straps carried by the saddle plate and passed about the lure to releasably secure the same, and means to releasably se-

cure the arm in a vertical position, the arm being adapted to be swung upwardly to a horizontal position when released from the holding means.

- 5 10. In a race track apparatus, an overhead track having upper rails spaced transversely from each other and a lower rail between the upper rails, a carriage movable along said track and including a body plate, wheels rotatably connected with the body plate and resting upon the lower rails, poles pivoted to the body plate and extending upwardly therefrom, axles extending in opposite directions from the poles, wheels rotatable about the axles and bearing against the upper rails, means to propel the carriage along the track, and means carried by the carriage to support a lure beneath the track in operative position to a race track.
- 20 11. In a race track apparatus, an overhead track having upper rails spaced transversely from each other and a lower rail between the upper rails, a carriage movable along said track and including a body plate, wheels rotatably connected with the body plate and resting upon the lower rails, poles pivoted to the body plate and extending upwardly therefrom, axles extending in opposite directions from the poles, wheels rotatable about the
- 25 20 axles and bearing against the upper rails, the upper rails being charged and the upper wheels being insulated from their axles, an electric motor carried by said body plate and grounded thereon and having conductors connected with the axles, means to transmit motion from the motor to the lower wheels, and means carried by the carriage to support a lure in operative relation to a race track.

In testimony whereof I affix my signature.
